Kahn & Goldstein

Patented Aug. 27, 1929.

UNITED STATES PATENT OFFICE.

HARRY ROGOVIN, OF BROOKLYN, NEW YORK.

PORTABLE LIGHTING DEVICE.

Application filed May 11, 1926. Serial No. 108,227.

This invention relates to portable lighting devices.

An object of the invention is to provide a lighting device of the character described, comprising a shaded lamp of improved construction adapted to be removably suspended from a support, so as to provide illumination for reading, toilet, decorative, and other purposes.

Another object of the invention is to provide a portable lighting device of the character described, constructed with extensibly collapsible parts adjustable for varying the distance of the light from a support, and adapted to permit packing quantities of such devices in compact form for shipping and storing.

A further object of the invention is to provide an improved device of the character described, which may be readily mounted on various supporting structures, which shall comprise few and simple parts assembled in a neat and attractive manner, and which is relatively cheap to manufacture, and practical and efficient to a high degree in use.

Other objects of this invention will in part be obvious and in part hereinafter pointed out.

Certain features herein shown and described are shown, described and claimed in my co-pending application Serial No. 108,288, filed in the United States Patent Office on the 11th day of May, 1926, and accordingly not claimed herein.

With the above exception, the invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a perspective view of a fragmentary portion of a headboard of a bedstead showing a bed lamp embodying the invention mounted thereon, parts of the latter being broken away to expose the interior.

Fig. 2 is a perspective view of the improved bed-lamp showing the hanger in collapsed position for shipment or storage.

Fig. 3 is a fragmentary sectional view showing the telescoping construction of the hanger arm, and

Fig. 4 is a perspective view of the im-

proved bed-lamp provided with a non-extensible form of hanger.

Referring in detail to the drawing, 10 denotes a portable lighting device embodying the invention in the form of a shaded bed-lamp which comprises a box-like shade 11 having a bottom opening 12. An electric socket and lamp 13^a are mounted in said shade, said shade, socket, and lamp being suspended as a unit by means of a hanger H from the headboard 14 of a bed.

The shade 11 may comprise a wire frame 15 having a covering 16 of suitable translucent sheet material, such as a decorative, textile fabric thereover, forming the sides and top of the shade. As here shown, the frame is constructed to include a pair of structural members 15^a and 15^b supporting the front 16^a and the rear side 16^b of the lamp shade covering, respectively, said members being held in spaced relation by suitable wire cross braces 17. The frame members and braces may be fastened together in any suitable manner, preferably by welding. Two of the braces 17^a connecting intermediate portions on opposite sides of the frame structure are preferably provided with loops 18 extending from the rear side of the shade 16^b, as is clearly shown in Fig. 2.

For mounting the socket and lamp 13^a, suitable means such as a brace 19 is supported between the frame members 15^a and 15^b at one end thereof, the lamp socket being secured to the brace 19 in any well understood manner. Said brace is preferably offset inwardly of the adjacent side of the shade as at 20 to provide a clearance for the passage of conductor wires 21 which may be connected to a suitable electric source (not shown).

The hanger H is preferably formed of wire and is bent to have spaced arms or branches 25, each terminating in end loops 22. Said arms have rounded engaging portions 23 which are interconnected by a middle spacer portion 24, the loop ends 22 pivotally engaging with the loops 18 of the braces 17^a.

To provide for adjustment of the length of the hangers, the arms 25 may be of any suitable telescoping construction, and as shown in Figs. 2 and 3, are provided with a slidably adjustable connection 26. To form said connection, the hanger arms 25 are made in two parts 25^a and 25^b having the ends of each provided with loops 26^a

and 26^b, respectively, the part 25^a passing through said loop 26^a and the part 25^b passing through the loop 26^b to permit relative sliding movement therebetween. The hanger is given a decorative appearance and is prevented from marring surfaces with which it may contact by providing a suitable resilient sleeving 27 thereon. The sleeving extends over the extensible connection 26 and may be provided with a slack portion 27^a to permit the extension and retraction of the arms 25 when adjusting the hanger.

In using the invention, the parts are assembled as shown in the drawings and may be suspended from the headboard 14 of the bedstead or from some other suitable support. The lamp and shade may be adjusted with relation to the headboard support by simply extending or contracting the hanger arms 25. For shipping bed-lamps in quantity lots or for storing same when not in use, the hanger, after the bed-lamp has been removed from its support, is swung so that the rounded engaging portion 23 is opposite the shade opening 12. The hanger arms 25 are then moved into retracted position so that said engaging portion 23 enters the opening 12, as is clearly shown in Fig. 2.

In Fig. 4 is shown the improved bed-lamp provided with a non-extensible hanger. Here, the hanger 113 is provided with hanger arms 125 which are proportioned so that on swinging the hanger from its effective position, shown in dotted lines, to its folded position shown in the full lines, the rounded engaging portions 132 will just pass over the rim of the shade opening 12, thereby forming a compact body for shipment or storage free from loose and projecting parts.

It will thus be seen that there is provided a device in which the several objects of

this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A portable lighting device of the character described, comprising a lamp shade having a bottom opening, a hanger secured to a side of the shade at a spaced distance from said opening, said hanger having a free end thereof formed with engaging means for mounting the device on a support, and means for pivotally securing the hanger to the shade for permitting the folding of said engaging means into said opening whereby the device is formed into a compact body for storage.

2. A portable lighting device of the character described, comprising a lamp shade having a bottom opening, an adjustably extensible hanger secured to a side of the shade at a spaced distance from said opening, said hanger having a free end thereof formed with engaging means for mounting the device on a support, said hanger being pivotally secured to the shade and adapted to be collapsed and swung so that said means are entered into said opening to form said device into a compact body for storage.

In testimony whereof I affix my signature.

HARRY ROGOVIN.
